UNITED STATES PATENT OFFICE

154,741

DESIGN FOR A COMBINED PIANO AND LIGHTING FIXTURE

Ray Blatt, Bronx, N. Y.

Application March 20, 1947, Serial No. 137,771

Term of patent 14 years

(Cl. D56—9)

To all whom it may concern:

Be it known that I, Ray Blatt, a citizen of the United States of America, residing at Bronx, New York, in the county of Bronx, State of New York, have invented a new, original, and ornamental Design for a Combined Piano and Lighting Fixture, of which the following is a specification, reference being had to the accompanying drawings, forming a part thereof.

Fig. 1 is a front perspective view of a piano showing my design, and Fig. 2 is a side elevational view thereof.

I claim:

The ornamental design for a combined piano and lighting fixture as shown.

RAY BLATT.
